UNITED STATES PATENT OFFICE

ROBERT W. TAIT, OF MYSTIC, AND CHARLES F. LEPPER, OF CENTERVILLE, IOWA

SQUARE

Application filed March 17, 1927. Serial No. 176,074.

This invention relates to tools, and its embodiment may best be set forth in the well-known steel square used in connection with the laying out of angles or the determining 5 of miter cuts for regular polygons.

The primary object of this invention is the provision of a square having degree designations associated with the indications in terms of inches which are ordinarily made a 10 part of the square.

Another object of the present invention is to provide a square having an auxiliary designation associated with each indication in terms of inches which auxiliary designation 15 is computed from a central point found by projecting intersecting lines from a predetermined point along each blade of the square.

A yet further object of the instant invention is the provision of a tool having auxiliary designations associated with the standard indications which will permit the computing of a miter cut for a regular polygon without having to resort to involved 25 computations.

Minor objects of the invention and specific details of construction will appear during the course of the detailed specification referring to the accompanying drawing, in which

Figure 1 is a perspective view of a square made in accordance with this invention.

Fig. 2 is a diagrammatical view of an L-square showing one method of reaching the proper degree designation to be associated 35 with each graduation thereon in terms of inches.

Fig. 3 is a diagrammatical face view of the square made in accordance with this invention being applied to work, and,

Fig. 4 is an enlarged fragmentary view of the face of a square made in accordance with this invention.

Similar reference characters refer to like parts throughout the several views, and the numeral 5 designates the longer blade of the square which joins the shorter blade 6 at one end of the "heel" of the square. The two blades 5 and 6 extend perpendicularly from each other and each has graduation marks 7 engraved or otherwise imprinted on

the face thereof adjacent the two edges and also adjacent the center of said faces.

In applying the improvement to an ordinary square, the inch graduations on the same are used in conjunction with the added 55 degree indications. However, this is only a matter of convenience, and the invention may be applied to a square in any suitable manner, according to the wishes of the manufacturer or user. In the instance illustrated 60 in the accompanying drawing, the auxiliary designations are associated with the graduations along the outer edge of each blade 5 and 6. Degree designations 8 are applied to the face of the square adjacent each indicator 65 9 and the arriving at the proper designation may be set down as follows:

Take, for example, the inch indicator "12" at the outer edge of each blade 5 and 6 respectively, extend or project a line 10 perpendicularly therefrom to a point 13 where the two intersect and there establish a central point for describing an arc 14. The next step may be to divide the arc 14 into 70 degrees, minutes and seconds, determine the degree line intersecting the outer edge of the blades 5 and 6 and each inch graduation mark therealong and then mark the proper associated degree designation on the face of the blade adjacent the inch graduation 7 and 75 indicator 9. In this example, since by construction the angle included between the lines 10 is 90 degrees, and also since the apex of the square bisects the arc of the circle subtended by this 90 degree angle, therefore, the 80 twelve inch indicator on each blade 5 and 6 respectively is on the 45 degree line extending from point 13 to arc 14. In marking smaller or larger squares, this predetermined 85 point may be closer or farther from the meeting ends of the two blades.

Fig. 3 illustrates one extremely simple manner of using a square made in accordance with this invention. The carpenter in this instance desires to form substantially a 60° 90° 95° angle when he cuts the board 15 in two without a large amount of computing or figuring. In this instance, since a 45° angle registers with the twelve inch graduation of each blade 5 and 6 respectively, and it is

desired to illustrate a use within the radius of 45° and 45° or the portion of the square between lines 10 as indicated in Fig. 2, the $60^\circ 59' 17''$ angle desired to be reached may be quickly found by placing blade 5 on board 15 with its twelve inch graduation at the lower edge of the board. With this point in place, blade 6 is swung around to position the seven inch graduation at the lower edge of board 15. The square is now in the relative position with respect to board 15 shown in Fig. 3. In this position, the line 16 may be drawn across the board. It will be at the angle desired. At blade 6, the angle of $60^\circ 59' 17''$ is presented; at blade 5, the complement of that angle or $29^\circ 43''$ is found.

Because of the relationship of the inch graduations 7 and the degree designations 8, the equation 7 is to 12 as 12 is to 21 is presented. By glancing at the degree designations associated with these figures on the novelly constructed tool, it will be found that the degree difference between the associated designations at the 7 inch and 12 inch graduation (blade 6) is 15 degrees. The angle desired is $60^\circ 59' 17''$ and the inch graduation at the designation reached when 15 is subtracted therefrom (45 degrees) is the twelve inch graduation (blade 5) or that 20 properly placed at the lower edge of the board as above set forth and shown in Fig. 3.

An instance of arriving at a $60^\circ 59' 17''$ cut when departing from the radius of 45° and 45° is simple, in that the designation closest to $60^\circ 59' 17''$ is located on the face of blade 5. As shown, this designation is at the twenty-one inch indicator. With this point in place at the lower edge of the board, the other blade 6 of the square is swung around to a place where the forty-five degree designation is also at the lower edge of the board 15. In this position, a line may be drawn across the board along the edge of blade 6. This line will be at the desired angle.

This principle of operation may be deducted from the above examples. To obtain a line for a cross cut of any desired angle, get the point on one of the blades at its outer edge which registers with the degree of the angle of the cut desired, then get the 45-degree point on the outer edge of the other blade. Place these two points on the same edge of the board to be marked, and the angle made by the second mentioned blade with the board will be the desired angle. This is true whether the angle to be obtained is greater or less than 45-degrees.

It is understood that many modifications in making a tool in accordance with this invention may be followed, and it is desired to be limited only by the scope of the appended claims.

Having thus described the invention, what

is claimed as new and desired to be secured by Letters Patent is:

1. A square of the kind described comprising a pair of blades extending perpendicularly to each other, each of said blades having graduations in inches marked along the outer edge thereof and degree and degree fraction designations associated with each graduation respectively, said degree designations being computed from a center point formed by intersecting lines drawn perpendicularly to each blade at the same distance from the heel of the square.

2. An L square of the kind described, comprising a pair of blades extending perpendicularly from each other, each of said blades having graduations in inches marked along the outer edge thereof and degree designations associated with each inch graduation, both of said degree and inch designations starting at the heel of said square at a zero point, the said degree designations being computed and set down along the outer straight edges of said square by projecting radial lines from a center point through each inch graduation, said point being determined by the intersecting of a perpendicular line drawn through inch graduations equidistant from the zero point on each blade.

In testimony whereof we hereunto affix our signatures.

ROBERT W. TAIT.

CHARLES F. LEPPER.
